UNITED STATES PATENT OFFICE.

HERBERT H. STEELE, OF MARCELLUS, NEW YORK, ASSIGNOR TO THE MONARCH TYPE-WRITER COMPANY, OF SYRACUSE, NEW YORK, A CORPORATION OF NEW YORK.

TYPE-WRITING MACHINE.

981,809.

Specification of Letters Patent. Patented Jan. 17, 1911.

Application filed December 11, 1908. Serial No. 467,056.

To all whom it may concern:

Be it known that I, HERBERT H. STEELE, citizen of the United States, and resident of Marcellus, in the county of Onondaga and State of New York, have invented certain new and useful Improvements in Type-Writing Machines, of which the following is a specification.

My invention relates to typewriting machines and more particularly to ribbon feed mechanism for such machines.

Heretofore it has been customary to rotate the winding or driven ribbon spool at a uniform rate, the velocity of the winding spool being constant relative to the travel of the carriage in the direction of its feed. Otherwise expressed, the driven spool has been given a uniform extent of rotation at each intermittent feed movement of the carriage. In such constructions, when a ribbon spool is being wound onto an empty or nearly empty spool, the longitudinal feed of the ribbon is comparatively slow and as the amount of ribbon wound on the spool increases the velocity of the ribbon through the printing field gradually increases in proportion to the increasing diameter of the winding on the core. This causes an irregular longitudinal feed of the ribbon past the printing field; a feed that is comparatively slow or short at the start and gradually increases as the opposite end of the ribbon is approached.

One of the objects of the present invention is to overcome the above difficulties and to provide improved means whereby the velocity and extent of rotation of the winding spool varies progressively according to the amount of ribbon wound on said spool for effecting a uniform travel of the ribbon past the printing field.

A further object of the invention is to prevent any excessive drag upon the spool from which the ribbon is being wound as the winding spool takes up the ribbon.

A still further object of the invention is to provide an improved ribbon reversing mechanism.

To the above and other ends which will hereinafter appear, my invention consists in the features of construction, arrangement of parts and combinations of devices to be hereinafter described and claimed.

In the accompanying drawings in which

like reference characters designate corresponding parts in the various views, Figure 1 is a fragmentary vertical fore and aft sectional view of the upper portion of one form of typewriting machine embodying my invention. Fig. 2 is a detail sectional view showing the disposition of the reversing device at the opposite side of the machine when that shown in Fig. 1 is positioned as indicated therein. Fig. 3 is a fragmentary front view with parts broken away and parts in section, and showing a portion of the ribbon feed and reversing mechanism. Fig. 4 is a fragmentary plan view of the same partly in section.

My present invention is in the nature of an improvement on the construction described in my application filed December 5th, 1908, Serial No. 466,124.

I have shown my invention embodied in a Monarch machine, although it should be understood that the invention is applicable to different styles of typewriting machines.

Corner posts 1 support a top plate 2 on which a suitable carriage (not shown) is mounted to travel from side to side of the machine, the carriage supporting a cylindrical platen 3. Type bars of the usual form are adapted to strike upwardly and rearwardly through an opening 4 in the top plate against the front face of the platen 3, a ribbon A being automatically interposed in the path of the type by the usual mechanism for actuating a ribbon vibrator 5. The ribbon A passes through guide openings in the ribbon vibrator from one spool 6 to the opposite ribbon spool 7. The ribbon spools are received in cups or containers 8 provided with guide openings 9 through which the ribbon passes. The carriage is connected in the usual manner to a spring drum 10 provided with a pawl 11 pivoted thereto and engaging a ratchet wheel 12 connected with a beveled gear 13 which in turn meshes with a companion beveled gear 14 secured to a transverse shaft 15 journaled in bearings in depending lugs 16 and 17 which project from the top plate. A beveled pinion 18 is secured to the right-hand end of the shaft 15 and a like beveled pinion 19 is secured to the left-hand end of the shaft. The hub of the pinion 18 bears against the depending lug 16 on one side thereof, whereas the hub of the beveled gear

14 bears on the opposite side of the depending lug 17, thus preventing a longitudinal movement of the shaft in its bearings. The left-hand beveled pinion 19 meshes with a beveled gear 20 secured to a shaft 21 journaled at its rear end portion in a depending lug 22 projecting from the top plate of the machine. The forward end of the shaft 21 is journaled in a depending projection 23 extending from the top plate. A member 24 surrounds the shaft 21 and is connected therewith by a spline 25 which takes within a spline groove in the member 24 and causes said member to rotate with the shaft 21 but 10 enables the member to be moved longitudinally of the shaft independently thereof. The member 24 has a friction roller 26 secured thereto for coöperation with a companion friction disk 27, the roller 26 and 15 disk 27 constituting two members of differential gearing as will hereinafter more clearly appear. A circular groove 28 is formed in the member 24 for the reception of inwardly projecting pins 29 carried by a 20 yoke 30. The yoke is carried by an arm 31 supported and controlled in a manner which will be hereinafter described. The friction disk 27 is fixedly mounted on a shaft 32 which at one end is received in a bearing 25 opening in the depending projection 23 and at its other end projects through a bearing opening in a depending bracket arm 33 secured to the top plate by a screw 34. The friction disk has fixed thereto a beveled 30 pinion 35 which meshes with a companion beveled pinion 36 secured to the lower end of an upright shaft 37 which extends through a bearing opening in the projection 23 and extends above the top plate and carries 35 at its upper end the left-hand ribbon spool 6. An upright shaft 38 is supported in a bearing 39 on the top plate and carries the arm 31 at the lower end thereof. The shaft 38 extends through an opening in the 40 top plate into an enlarged portion 40 of the cup 8 of the left-hand ribbon spool. The shaft 38 has an arm 41 secured to the upper end portion thereof, the arm being situated at a height where it is adapted to 45 swing into the space between the flanges of the ribbon spool. The free end of the arm 41 is provided with a yoke 42 which receives a contact device or roller 43 journaled in the yoke at 44. This roller is adapted to bear upon the coil of ribbon on the left-hand ribbon spool, as shown in Fig. 4. An arm 45 is connected to the collar of the arm 41 and extends through an opening 46 in the enlarged portion 40 of the ribbon spool cup. 50 The arm 45 is provided with a finger piece 47 at the outer end thereof by which the arm 41 may be moved to the dotted line position within the enlargement 40, as shown in Fig. 4, so as to clear the arm 41 55 of the ribbon spool so that the latter may

be readily removed from the machine if desired. An expansion spring 48 surrounds the shaft 21 and bears on one end against a sleeve 49 that is secured by a screw 50 to the shaft 21 and at its opposite end the 70 spring bears against the member 24 so as to tend to force it and the friction wheel 26 toward the axis of the friction disk.

From the foregoing description it will be understood that the intermediate connections between the roller 43 and the member 24 automatically varies the position of the friction roller 26 with reference to its companion friction disk 27, according to the amount of the ribbon on the winding spool. Thus as the coil of ribbon on the winding spool increases the roller 43 will be forced toward the dotted line position and the friction roller 26 will through the shaft 38 and arm 31, be gradually moved away from the 80 axis of the friction disk toward the periphery thereof and a variation in the speed and extent of movement of the ribbon spool will be effected, depending on the amount of ribbon wound on the winding spool. There 90 is therefore an automatic compensation in the feed for the increased amount of ribbon wound on the winding spool and the ribbon will be fed past the printing field a uniform 95 distance at each intermittent feed movement 95 of the carriage irrespective of the amount of ribbon wound on the winding spool.

I have described the connections between the shaft 15 and the left-hand ribbon spool 6. It should be understood that like connections are employed between the right-hand ribbon spool 7 and the shaft 15, and further detailed description of the duplicated parts at the other side of the machine is therefore deemed unnecessary. The corresponding parts at the other side of the machine will be indicated by the same reference numerals employed to designate the connections already described.

Each shaft 32 which carries a friction disk 110 27, extends beyond its supporting bracket 33 and a leaf spring or reversing device 51 bears against the projecting conical end of the shaft so as to force the friction disk into contact with its companion friction wheel 26 115 and maintain an effective engagement between the companion beveled gears 35 and 36. Each leaf spring 51 is in the nature of a bell crank lever which is pivoted on a shoul- 120 dered screw 52 by which it is mounted on the associated bracket 33. Each leaf spring has an opening 53 therein which is of a size to correspond substantially to the diameter of the associated shaft 32 and is adapted to register therewith when the leaf spring is 125 moved around its pivot 52. Forwardly extending arms 54 on the leaf springs are received in horizontally disposed slots 55 in a segmental reversing device 56 that extends from one side of the machine to the other 130

and is pivoted centrally on a shouldered screw 57 secured to the front plate 58 of the machine. Depending ears 59 are formed on the segmental reversing device by which forwardly projecting finger pieces 60 are secured to the device; the finger pieces extending through slots 61 in the front plate 58. By swinging the reversing device 56 around its pivot by means of either of the finger pieces 60 the positions of the leaf springs 51 are varied to bring the closed portion 62 of one of them into contact with the end of the shaft 32 and to bring the opening 53 in the other spring into register with the associated shaft. When the portion 62 engages the end of the associated shaft the spring exerts a longitudinal pressure on the shaft to maintain a frictional engagement between the associated disk 27 and its coöperating friction wheel 26, thus operatively connecting these parts to effect a rotation of the friction disk through the intermediate gearing between the spring drum and said disk, and to turn, say, the left-hand ribbon spool through the intermediate gearing between the friction disk and said spool. On the other hand, the opening 53 in the other leaf spring 51 is at this time in register with its shaft 32 and the pressure of the spring is released from the associated shaft and there is no pressure to maintain a frictional connection between the right-hand friction disk 27 and its companion friction wheel 26, so that the spool 7, its shaft 37 and the friction disk (if the bevelled pinion 35 of the latter is in mesh with the pinion 36) will be rotated independently of its shaft 21 and other associated parts of the train when the ribbon is being wound on the ribbon spool 6. It should be understood that the conoidal ends of the shafts 32 act as cams to flex the springs 51 when the latter are moved to bring the closed portions 62 of the springs against the ends of the shafts.

From a comparison of Figs. 1 and 2 it will be understood that when one leaf spring or reversing device 51 engages its shaft to operatively connect the companion friction disk and wheel of one ribbon spool, the leaf spring 51 at the other side of the machine will have the opening therein in register with its shaft so as to relieve the companion friction gears from pressure, and thus render them inoperative.

From the foregoing description it will be understood that the ribbon mechanism is driven from the spring drum which is situated in the rear of the machine; that the shaft 15 is a main driving shaft which is at all times maintained in mesh with the gears of the secondary driving shafts 21; that these secondary driving shafts are operatively connected to the ribbon spools through differential gearing and that in order to effect a reversal in the direction of the feed, the connections between the secondary driving

shafts and the ribbon spools are rendered operative or inoperative in accordance with the spool to be driven. It will likewise be understood that when one spool is being driven there is no essential drag on the spool from which the ribbon is being unwound, and that the connection and disconnection between the ribbon spools and the driving mechanism is effected between the secondary driving shafts and the spools and near the ribbon spools and at or near the front of the machine. The ribbon mechanism of my present invention is particularly well adapted to feeding an ink "ribbon" of paper having the "ink," carbon, or pigment on the side next to the platen and being uninked or plain on the opposite side thereof.

Certain of the features herein shown and described are claimed broadly in my application hereinbefore referred to, the present invention being restricted to features not disclosed in my said prior application.

By "differential gearing," I mean gearing in which the speed ratio can be changed. As shown in the present case, this is done by moving the wheel 26 toward or from the axis of the disk 27.

What I claim as new and desire to secure by Letters Patent, is:—

1. In a typewriting machine, the combination with a pair of ribbon spools, driving means for said spools, said driving means including differential gearing for each spool and automatic means for changing said gearing to change the feed of the driven spool in accordance with the amount of ribbon wound thereon; and means for effecting an operative disconnection between the members of the differential gearing of one spool and for concurrently effecting an operative engagement between the members of the differential gearing of the other spool.

2. In a typewriting machine, the combination of a ribbon spool; driving mechanism therefor, said driving mechanism including differential gearing, means controlled by the amount of ribbon on the spool for determining the relation between the members of said differential gearing; and hand-actuated means operable at will for throwing the members of said differential gearing into and out of coöperative relation.

3. In a typewriting machine, the combination of ribbon spools; means for rotating said ribbon spools; means for varying the extent of feed imparted to the driven spool during the different intermittent rotations of the spools in accordance with the amount of ribbon wound on the winding spool, said varying means including a contact device associated with each ribbon spool and bearing on the ribbon wound thereon; and hand-actuated means operable at will for throwing the members of the varying means of one ribbon spool out of coöperation and for

concurrently throwing the members of the varying means of the other ribbon spool into coöperation.

4. In a typewriting machine, the combination of ribbon spools; driving mechanism therefor, said driving mechanism including differential gearing associated with each ribbon spool; means, including a contact device which bears on the ribbon on each spool, for automatically varying the relation between the members of the differential gearing as the ribbon is wound on the winding spool; and hand-actuated means operable at will for throwing the members of the differential gearing of one spool out of coöperation and for concurrently throwing the members of the differential gearing of the other spool into coöperation.

5. In a typewriting machine, the combination of a ribbon spool; means controlled by the feed movement of the carriage for turning the ribbon spool, said means including differential gearing; automatically actuated means for changing said differential gearing to vary the feed of the driven spool; and hand-actuated means operable at will for throwing the members of said differential gearing into and out of coöoperative relation.

6. In a typewriting machine, the combination of ribbon spools; means controlled by the feed movement of the carriage for turning the ribbon spools, said means including differential gearing associated with each ribbon spool; automatically actuated means for changing said differential gearing to vary the feed of the driven spool, said automatically actuated means including a contact device which bears on the surface of the ribbon of each of the spools and whose position is altered in accordance with the amount of ribbon on the associated ribbon spool; and hand-actuated means operable at will for throwing the differential gearing of one of said ribbon spools out of coöoperative relation and for concurrently throwing the differential gearing of the other of said ribbon spools into coöoperative relation.

7. In a typewriting machine, the combination of ribbon spools; means for intermittently rotating said ribbon spools; means, which include a contact device that bears on each of the ribbon spools and differential driving means controlled by said contact device for varying the extent of feed of the winding spool during the different intermittent rotations of the spools in accordance with the amount of ribbon wound on the winding spool, the ribbon as it is wound on the winding spool forcing the associated contact device away from the axis of the spool; a spring for forcing each contact device toward the axis of its associated ribbon spool; and hand-actuated means operable at will for throwing the members of the differential driving means of one ribbon spool

out of coöperation and for concurrently throwing the members of the differential driving means of the other ribbon spool into coöperation in order to effect a change in the direction of feed of the ribbon.

8. In a typewriting machine, the combination of a ribbon spool; driving mechanism therefor, said driving mechanism including a driving disk and a coöperative driving wheel; automatically actuated means for effecting a relative movement between the wheel and disk toward and from the axis of the disk to vary the feed of the ribbon spool; and hand-actuated means operable at will for throwing the disk and wheel into and out of coöoperative relation.

9. In a typewriting machine, the combination of a ribbon spool; driving mechanism therefor, said driving mechanism including a driving disk and a coöperative driving wheel; means for effecting a relative movement between the wheel and disk toward and from the axis of the disk to vary the feed of the ribbon spool, said last mentioned means including a contact device that bears on the spool; and hand-actuated means operable at will for throwing said disk and wheel into and out of coöoperative relation.

10. In a typewriting machine, the combination of ribbon spools; driving mechanism therefor, said driving mechanism including a driving disk and a coöperative driving wheel for each spool; means for effecting a relative movement between the wheel and disk of the driven spool toward and from the axis of the disk to vary the feed of the driven spool, said last mentioned means including contact devices each bearing on the ribbon on the companion spool; hand-actuated means for moving said contact devices away from the ribbon; and hand-actuated means operable at will for throwing the driving disk and wheel of one ribbon spool out of coöperation and for throwing the driving disk and wheel of the other ribbon spool into coöperation.

11. In a typewriting machine, the combination of a ribbon spool; driving means for said spool, said driving means including differential feed devices; a swinging device contacting with the ribbon on the spool; intermediate connections between the swinging device and one of the differential feed devices to automatically effect a change in the extent of feed movement of the spool effected by the driving means; and hand-actuated means operable at will for throwing said differential feed devices into and out of coöoperative relation.

12. In a typewriting machine, the combination of ribbon spools; driving means for said spools, said driving means including differential feed devices associated with each ribbon spool; a swinging device contacting with the ribbon on each spool; intermediate

- connections between each swinging device and one of the differential devices of the associated ribbon spool to automatically effect a change in the extent of feed effected by the 5 driving means; hand-actuated means connected with each swinging device to throw it out of coöperation with the ribbon on the associated ribbon spool; and hand-actuated means operable at will for throwing 10 the differential feed devices of one spool into coöperation and for throwing the differential feed devices of the other spool out of coöperation in order to effect a reverse in the direction of the feed of the ribbon.
- 15 13. In a typewriting machine, the combination of a spring drum for the carriage; a ribbon spool; intermediate driving mechanism between the spring drum and ribbon spool, said driving mechanism including 20 differential feed devices; a movable device contacting with the ribbon on the spool; intermediate connections between said movable device and one of said differential devices, to automatically change the extent 25 of feed effected by the driving means; and hand-actuated means operable at will for throwing the differential feed devices into and out of coöperative relation.
14. In a typewriting machine, the combination of a power driven carriage; a ribbon spool; a rotating device for turning said spool; a coöperating actuating device operated by the power employed to move the carriage; automatically actuated means for 30 varying the distance from the center of rotation of said rotating device at which it co-operates with said coöperating actuating device; and hand actuated means operable at will for throwing said rotary device and its 35 coöperating actuating device into and out of coöperative relation.
15. In a ribbon mechanism for typewriting machines, the combination of a ribbon spool; two coöperating rotary actuating devices for rotating said spool; means operating automatically to vary the distance from the center of rotation of one of said devices at which it coöperatively engages with the other of said devices; and means operable 40 at will for throwing said rotary actuating device into and out of coöperative relation.
16. In a typewriting machine, the combination of ribbon spools, differential gearing for each of said spools, and means for throwing the members of the differential gearing for one spool into coöperation and for concurrently throwing the members of the differential gearing for the other spool 45 out of coöperation.
- 60 17. In a typewriting machine, the combination of a spring drum for the carriage, ribbon spools, intermediate operative connections between the spring drum and ribbon spools, said connections including differential actuating devices for each spool, and

- reversing means for operatively connecting the differential actuating devices of one spool and for concurrently disconnecting the differential actuating devices of the other spool. 70
18. In a typewriting machine, the combination of ribbon spools, driving means therefor including a friction disk and a co-operative wheel for each spool, means for varying the relation between each disk and wheel, and reversing means for throwing the friction disk and wheel of one spool into coöperation and for concurrently throwing the wheel and friction disk of the other spool 75 out of coöperation. 80
19. In a typewriting machine, the combination of a spring drum for the carriage, ribbon spools, intermediate gearing between said spring drum and said ribbon spools, said intermediate gearing including a friction disk and wheel for each spool, means for automatically varying the relation between each disk and its coöperative wheel, and hand controlled reversing means operable at will for throwing the wheel and disk 85 for one spool into coöperative relation and for concurrently throwing the wheel and disk of the other spool out of coöperative relation. 90
20. In a typewriting machine, the combination of ribbon spools, a spring drum for the carriage, a main driving shaft turned by the drum, secondary driving shafts, one for each ribbon spool, constantly maintained 95 geared connections between said main and secondary driving shafts, differential gearing between said secondary driving shafts and the ribbon spools, and reversing means for throwing the members of the differential gearing for one ribbon spool out of coöperation and for concurrently throwing the members of the differential gearing for the other ribbon spool into coöperation. 100
- 105 21. In a typewriting machine, the combination of ribbon spools, a spring drum for the carriage, a main driving shaft turned by the drum, secondary driving shafts, one for each ribbon spool, constantly maintained geared connections between said main and secondary driving shafts, a friction wheel 110 and disk between each secondary driving shaft and the companion ribbon spool, means for automatically varying the relation between the wheel and disk of each spool; and reversing means for throwing the friction wheel and disk for one spool out of coöperation and for concurrently throwing the friction wheel and disk of the other spool into coöperation. 115
- 120 22. In a typewriting machine, the combination of ribbon spools, driving means for said spools, said driving means including coöperative frictional driving devices for each ribbon spool, and spring-pressed means for maintaining coöperative relation be- 125
- 130

tween said coöperative frictional driving devices, and reversing means for applying said spring-pressed means to the driving devices of one spool and for concurrently relieving 5 the pressure of said spring-pressed means on the driving devices of the other spool.

23. In a typewriting machine, the combination of ribbon spools, driving means for said spools, said driving means including 10 a coöperative friction disk and wheel for each ribbon spool, and spring-pressed means for maintaining a frictional engagement between said disks and wheels, automatically actuated means for varying the relation 15 between each friction disk and wheel, and reversing means for applying said spring-pressed means to the friction disk and wheel of one spool and for concurrently relieving the pressure of said spring-pressed 20 means on the friction disk and wheel of the other spool.

24. In a typewriting machine, the combination of ribbon spools, driving means for said spools, said driving means including a 25 coöperative friction disk and wheel for each ribbon spool, a spring adapted to bear against the shaft of each disk to press the shaft endwise and thus maintain an operative engagement 30 between that disk and its wheel and reversing means for concurrently releasing the pressure of one spring and for applying the pressure of the other spring to render the driving means inoperative on one spool and operative on the other.

35 25. In a typewriting machine, the combination of ribbon spools, gearing for said ribbon spools, shafts for said gearing, and means for reversing the direction of feed of the ribbon, said means comprising springs 40 adapted to bear on certain of said shafts to maintain an operative engagement between certain of the gears, and hand-actuated means for concurrently moving one of said springs into coöperative relation with its 45 shaft and the other spring out of coöperative relation with its shaft.

26. In a typewriting machine, the combination of ribbon spools, gearing for said ribbon spools, shafts for said gearing, and 50 means for reversing the direction of feed of the ribbon, said means comprising springs adapted to bear endwise on certain of said shafts to move the shafts longitudinally and to maintain an operative engagement be- 55 tween certain of the gears, and hand-actuated means for concurrently moving one of said springs into coöperative relation with

its shaft and flexing the spring, and moving the other spring out of contact with its shaft.

60 27. In a typewriting machine, the combination of ribbon spools, gearing for driving said spools, shafts for said gearing, and reversing mechanism for changing the direction of the feed of the ribbon, said reversing 65 mechanism comprising two leaf springs, each adapted to exert a force endwise on a shaft for one of said ribbon spools and to maintain an operative engagement between certain of the gears of the companion ribbon spool, and hand-actuated shiftable means for concurrently throwing one of said springs out of operation on its coöperating shaft when the other spring is moved into position to bear on the shaft 70 with which it coöperates.

75 28. In a typewriting machine, the combination of ribbon spools, driving means therefor including a set of friction gears for each spool, and reversing means coöperative 80 with the friction gears to render them operative or inoperative, said reversing means comprising two springs, one for each set of friction gears, said springs maintaining an operative engagement between 85 the friction gears of each set, and means for concurrently rendering one spring operative when the other is rendered inoperative.

90 29. In a typewriting machine, the combination of ribbon spools, driving means therefor including a set of friction gears for each spool, shafts for said friction gears, and reversing means coöperative with one of the shafts of each set of friction gears to render the friction gears operative or inoperative; said reversing means comprising two pivoted springs, one for each set of friction gears, said springs each being coöperative 95 with one of the shafts of the companion set of friction gears to maintain an operative engagement between the members thereof, and hand-actuated means for moving one of said springs around its pivot into coöperation 100 with its companion shaft when the other spring is turned around its pivot to move it out of coöperative relation with its shaft.

105 Signed at Syracuse, in the county of Onondaga, and State of New York this 9th day of December A. D. 1908.

HERBERT H. STEELE.
